UNITED STATES PATENT OFFICE.

DAVID P. OLSON AND SAMUEL C. SWARTZFEGER, OF WASHINGTON, PENNSYLVANIA.

DINNER-PAIL.

1,032,622.

Specification of Letters Patent. Patented July 16, 1912.

Application filed April 20, 1912. Serial No. 692,172.

To all whom it may concern:

Be it known that we, DAVID PAUL OLSON and SAMUEL C. SWARTZFEGER, citizens of the United States, residing at Washington, 5 in the county of Washington and State of Pennsylvania, have invented certain new and useful Improvements in Dinner-Pails, of which the following is a specification, reference being had to the accompanying 10 drawings.

This invention relates to improvements in dinner pails, and particularly those which are constructed of metal and are collapsible.

An object of this invention is to provide 15 a pail of simple construction in which a coffee or tea can may be carried when the pail is in either open or collapsed form.

Another object of this invention is the provision of a dinner pail which when 20 folded may be easily carried in a coat pocket.

For a full understanding of the invention reference may be had to the following description and to the accompanying drawings, in which:—

25 Figure 1 is a perspective view of our improved dinner pail; Fig. 2 is a vertical section thereof; Fig. 3 is an end view of the device closed; Fig. 4 is a detail section of the pail closed; Fig. 5 is a detail section 30 showing the hook; and Fig. 6 is a detail view of a modified form of the hook.

Throughout the following description and on the drawings similar parts are referred to by like characters of reference.

35 Referring more particularly to the drawings the numeral 1 indicates the bottom of the pail which is preferably rectangular in form and is provided with side flanges 2 and end flanges 3.

40 Pivottally secured to the side and end flanges are side walls 4 and end walls 5 respectively which are adapted to fold inwardly when the pail is collapsed. The side and end walls of the pail are connected 45 rigidly at the corners thereof by means of angular or hinged hooks 6 which are carried by the end walls and engage staples or other suitable members 7 secured to the side walls. A can 8 which is slightly smaller

50 than the pail is adapted to fit therein and is supported by the angular portions of the hooks 6. The can which is adapted to contain a beverage such as coffee, tea, or the like is formed with a neck 9 on the top 55 thereof on which a cap 10, which may be

used as a drinking cup if desired, is secured by screw threads or other suitable means. The cap 10 of the can 8 is flush with the upper edges of the walls of the pail and the can is held securely in position by the cover 60 11 of the pail which rests upon the cap when the said cover is in position.

When it is desired to collapse the pail it will only be necessary to remove the can, whereupon the hooks 6 may be disengaged 65 from the members 7 and the walls permitted to fall outwardly, so that the can may be placed in the bottom section of the pail. The walls may then be folded inwardly on the can and the cover 11 may be placed in 70 position to completely inclose the walls and can within the bottom section of the pail.

The cover is securely held in position on the pail when it is either open or folded by means of hooks 12 which are adapted to 75 engage staples or eyes 13 secured to the side walls and bottom flanges of the pail. Slots 14 are formed in the cover adjacent the hooks 12 to slidably engage the staples or eyes 13.

80 It will be understood from the drawings that the hooks 6 will connect the walls of the pail and at the same time prevent the coffee can from slipping down into the pail. As shown in Fig. 6 at 6' the hooks may be 85 hinged to facilitate their engagement with the staples or eyes 7.

Having thus fully described our invention what we claim and desire to secure by Letters Patent, is:—

90 A collapsible pail comprising a bottom section having end and side flanges, end and side walls pivotally secured to the said end and side flanges of the bottom section, a cover, angular hooks connecting the end and side walls at the corners thereof, a can provided with a cap carried by the said pail and adapted to rest upon the angular hooks, the said cap being flush with the top of the pail, and the cover adapted to rest upon the 95 said cap of the can whereby the can is rigidly supported in the pail.

100 In testimony whereof we hereunto affix our signatures in the presence of two witnesses.

DAVID P. OLSON.

SAMUEL C. SWARTZFEGER.
